ATTRITION MILL

Isidor Chesler, Oceanport, N. J., assignor to Eagle
Pencil Company, New York, N. Y., a corporation
of Delaware

Application September 13, 1940, Serial No. 356,611

6 Claims. (Cl. 83—46)

My present invention relates to the art of pulverizing granular material such as graphite, clay, coal, sandstone, cinder, cement, ore and the like.

It is an object of the invention to provide a simple method and correspondingly simple apparatus for expeditiously and reliably pulverizing material of the above character to substantially any selected degree of fineness, even to the utmost fineness required in the industrial arts.

Another object is to provide a pulverizing mill which shall be highly efficient for its intended purpose and yet be simple and compact in construction with the elimination of swinging hammers, blades, paddles, rotors or other impacting elements, and which shall operate without waste or dust.

Another object is to provide a mill of the above type, in which the material is comminuted by attrition without adulteration thereof by particles gouged out of the attrition mill and with substantial elimination of wear on the latter and the avoidance of the need for periodical replacement of worn parts.

Another object is to provide a mill of the above type which may be operated without the need for expert care or attention and in which, as long as a sufficient supply of raw material is maintained, feed to the machine at the required rate occurs inherently throughout operation and in which, the material to be comminuted is inherently retained in the attrition chamber of the mill without resort to valves, restrictions or baffles to impede its escape, during the period of time required to effect comminution to the degree desired under the high propulsive force of the comminuting agency.

According to the invention expansive fluid under high pressure is preferably admitted at various parts of the length of a column of the raw material confined against lateral spreading and so tightly packed that it can advance but slowly under the propulsive force and that must give way by attrition for escape of the fluid. The bulking of the material resulting in such attrition affords increased opposition to the advance of the pressure fluid for progressively increased attrition and comminution from the inlet to the discharge end of the column. The mill is preferably used for pulverizing dry material of granular form and the comminuting agency is a gas or vapor, usually introduced at high temperature and high pressure. In a preferred construction of mill the attrition is effected in an elongated strong-walled metal pipe, preferably

disposed in a number of convolutions for compactness of installation.

While any desired method or means may be used for packing the raw material into the attrition pipe or other confined column and replenishing such column as comminuted end product is discharged therefrom, it is preferred to maintain the column packed by means of an injector connected in the path of high pressure gas flow and communicating with the source of raw material, preferably with the bottom of the supply chamber therefor. The attrition chamber discharges to a separator affording an elongated course for the released gas and the entrained particles. The separator may have one or more spouts applied at intermediate parts thereof to draw off by gravity finer comminuted particles that are somewhat coarser than the finest grade thereof which alone is sufficiently light to be levitated by the gas through the ultimate delivery of the separator.

The supply chamber for the raw material is in communication with the separator, being preferably disposed directly therebelow, with previous connection through which gas pressure may be relieved, thereby to minimize the opposition to gravity return from the separator to the supply container of any coarser comminuted particles discharged from the attrition chamber.

In the accompanying drawing in which are shown one or more of various possible embodiments of the several features of the invention,

Fig. 1 is a diagrammatic sectional view of the attrition mill, taken on line 1—1 of Fig. 2,

Fig. 2 is a plan view of the attrition coil,

Fig. 3 is a diagrammatic view on a larger scale illustrating the mode of operation in the attrition chamber and

Fig. 4 is a fragmentary sectional view illustrating an arrangement for determining a coarser degree of comminution.

Referring now to the drawing, the mill comprises a supply container 10 for the raw material, which feeds downward from the inclined floor 11 thereof through an outlet 12 delivering to pipe 13 plugged at its end 14 and provided with an angular projection 15 into which is fitted an injector jet 16 through which high pressure fluid, preferably air or steam, is admitted by way of pipe 17.

The pipe 13 may extend vertically upward at 18 is preferably made of extra heavy steel tube and has a substantial length thereof coiled as a multiplicity of convolutions 19 constituting the attrition chamber, which may encircle the sep-

arator 20 shown directly above the supply container 10. The supply container 10 and separator 20 have aligned necks 21 and 22 respectively, connected by a sleeve 23 of canvas to permit venting of gas pressure for the purpose hereinafter set forth.

The delivery end 24 of the attrition coil 19 opens into the outer shell 25 of the separator which preferably is built with a plurality of spaced concentric cylindrical walls 26, 27, and 28, wall 26 being rigidly connected to the top wall 29 of the separator and wall 27 being supported by means of an oblique downwardly extending spout 30 protruding through the neck 22 while the inner wall 28 protrudes through the top 29 of the separator to which it is connected and extends as a conduit 31 to the settling chambers (not shown).

The supply container 10 derives the raw material from a hopper 32 delivering thereto by means of a flight conveyor 33 turned by a pulley drive 34. To prevent the raw material from becoming clogged in the supply container, a vertical flight conveyor 35 may be slowly turned by pulley drive 36 at the upper end of a shaft 37 extending the height of the mill. Alternatively an appropriate pneumatically or electrically operated vibrator of conventional construction (not shown) may be employed to act by percussion against floor 11 of the container 10 for the purpose set forth.

The attrition coil is preferably provided with a multiplicity of jets 38 spaced along the length thereof, for delivering pressure fluid thereto. Illustratively these nozzles are uniformly distributed as shown, are welded to the coil and deliver tangentially, four such jets ninety degrees apart being shown for each convolution. A manifold comprising a plurality of vertical inlet pipes 39 supplied from a common inlet 40 connected by cross pipes 41 may be used to supply said various jets 38 with air or steam at high pressure from the same source as supplies jet 16.

The raw material 43 should preferably be dry and in granular form not larger than four mesh. It should be lodged in the supply chamber to a depth sufficient to be taken up by the injector 16 as rapidly as the injector will take it. In practice this could be to a level indicated at 42, approximately midway between the injector 16 and the conveyor 33, the container 10 being about one-third full. Pressure fluid, usually a gas or a vapor, desirably superheated steam but preferably air at a temperature of about 650° F. and at pressure in excess of 75 pounds per square inch is employed.

In operation, hot air or steam is preferably first passed through the empty mill to heat all parts uniformly. When the supply container 10 is now charged to the desired level 42 the further supply of the hot expansive fluid through jet 16 into empty attrition coil 19, causes the injector 16 to entrain the raw material 43 at a fast rate, so that it becomes crowded and to some degree crushed in the attrition coil 19, and as it becomes thus packed in a column filling and blocking said coil, the aspirating action at the injector 16 is correspondingly diminished and the high pressure fluid from jets 16 and 38, as it forces its way through the packed column causes the particles to be broken up by mutual friction or attrition. As the material becomes progressively reduced in size in the movement and expansion of the gas through the elongated attrition coil its bulking value increases within

the confines of the coil length and more frictional resistance is engendered with correspondingly further attrition. The series of jets 38 of compressed air or steam distributed along the length of attrition coil 19 assure the supply of steam or air of adequate pressure, even through the most closely packed material near the delivery end of the attrition pipe. As illustrated in Fig. 3, the particles become progressively finer from the inlet to the delivery end of the attrition coil in the forceful propulsion of the compressed air or steam therethrough.

Despite the fact that the attrition pipe is of uniform diameter throughout its length, without restrictions or obstruction, and the applied air or steam pressure is of high magnitude, the material is yet greatly retarded in its advance through the attrition chamber, thereby to be subjected to the attrition action for a period of time sufficiently long to reduce it to the desired degree of fineness under the expansive and propulsive force of the gas, much of the energy of which becomes dissipated in the attrition chamber, and the action occurs automatically without the need for adjustment.

In the operation set forth the gas forces its way for attrition and slow advance of the particles packed in the coil 19 and the major attrition action occurs between said particles and little friction under the outward expansive action of the steam or air is incurred at the smooth inner wall of the coil, little or no movement occurring therealong, so that the pipe wall shows little or no evidence of wear even after prolonged service.

As comminuted product is delivered to the separator 20 the aspirating action at injector 16 will be sufficient to entrain more raw material to the inlet of the attrition pipe, thereby automatically to maintain the same charged or packed so that the comminution proceeds without the need for attention as long as the supply chamber is adequately charged with raw material from the hopper 32. The jet 16 serves thus, automatically to pack the stock into the attrition coil and to keep the same at all times packed with stock, while jets 38 serve as the pulverizing agency, assisted to some extent by the residual effectiveness of the air or steam pressure from jet 16.

While the mill described and diagrammatically shown in the drawing is a desirable practical embodiment, it is understood that wide departures are possible within the scope of the invention. Manifestly the attrition chamber shown in the form of a coiled pipe might be arranged in any of a variety of other ways, although it is preferred so to dispose the conduit as to afford a mill of small bulk. The conduit for instance might extend rectilinearly along the walls of the chamber or its convolutions might extend about the neck or about the supply container 10, or about the entire height of the apparatus. Where extra fine material is required it may be obtained by making the pipe of correspondingly greater length or by introducing the pulverized material in one or more further passes through the mill.

Those skilled in the art may design mill structures other than that illustratively shown herein by which the method claimed may be carried out and by which the raw material, closely confined in a column is caused to be comminuted by attrition under high pressure expansive fluid forced therethrough.

In Fig. 4 is shown a modification in which the

pipe is provided with a plurality of removable plugs 44 for selective application of a by-pass pipe illustratively shown at 45, to shorten the effective length of the attrition coil by short circuiting one or more convolutions thereof, for pulverization to any selective degree of fineness less than that effected by use of the full length of coil 19.

As the fine particles are driven out of the attrition pipe through the outer shell 25 of the separator, the coarser elements thereof will separate, dropping by gravity as indicated by arrows 46, upon the raw material 43 in the supply container 10, the venting of air or steam through canvas sleeve 23 precluding any back pressure that might impede such gravity return. The finer particles are levitated with the steam or air upward between walls 26 and 27 and thence directed downward between walls 27 and 28 where separation again takes place, the heavier particles dropping by gravity for collection in an appropriate bin (not shown) under spout 30, the finest particles being levitated through pipe 28 to settling chambers (not shown).

Pulley 34 is driven at such rate as to cause the hopper 32 to maintain the supply container 10 charged substantially to the desired level 42, in other words to supply fresh raw material at substantially the combined rate at which it discharges through spout 30 and outlet duct 31.

As many changes could be made in the above construction and method and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. An attrition mill unit comprising a supply container for granular material, a separator thereabove, an attrition pipe connected at its lower end to the bottom of said supply container and coiled near its upper end in a plurality of convolutions about said separator and delivering thereto, means for injecting gas under high pressure both through the lower end of said pipe and through one or more points along the coiled part of said pipe, the inlet part of said separator communicating directly with said supply container, the outlet of said separator discharging the finely pulverized material.

2. An attrition mill comprising a supply container for granular material, a separator thereabove, an attrition pipe connected at its lower end to the bottom of said supply container and coiled near its upper end in a plurality of convolutions about said separator and delivering thereto, means for supplying gas under high pressure to the lower end of said pipe and an injector in communication with the lower end of said supply container and discharging into said pipe, the inlet part of said separator communicating directly with said supply container, the outlet of said separator discharging finely pulverized material, an intermediate portion of the separator having a discharge spout associated therewith for delivering an intermediate grade of pulverized material.

3. An attrition mill comprising a source of granular stock, a helical pipe of substantially uniform diameter, and of a length at least one

hundred times its diameter, having an inlet communicating with said source and having an outlet, an injector near said inlet and directed lengthwise of the pipe to entrain granular stock thereinto, a plurality of jets distributed along the length of said pipe and directed tangentially thereof and toward said outlet, a source of gas under high pressure, delivering to said injector and to said plurality of jets, the length and diameter of pipe, and the means for feeding from the source being so proportioned and arranged as to provide for packing granular stock into the pipe and maintaining the same packed as comminuted material is ejected therefrom.

4. An attrition mill comprising a strong walled helical metal conduit substantially uniform in diameter, small relative to its length, a supply container for granular material to be pulverized, said conduit having an inlet communicating with said container and having an outlet, means for applying high pressure gas to said conduit, means for introducing high pressure gas into said conduit at various points along the length thereof and directed toward said outlet and including an injector connection to said container, to feed granular material into said conduit, a separator about which the outer part of said conduit is coiled and into which the outlet of said conduit delivers and in which residual gas pressure is dissipated, the length and diameter of pipe and the means for feeding material to be comminuted being so proportioned and arranged as to provide for packing such material into the pipe and automatically to determine the subsequent rate of injection in accordance with the rate of discharge of comminuted material under the attrition effect resulting from the flow and expansion of the gas in the column of granular material packed into the conduit.

5. An attrition mill comprising a separator, a metal attrition pipe helically coiled about and discharging into said separator, said pipe being of substantially uniform diameter, small relative to its length, a container below said separator, charged with the granular material to be pulverized and communicating with said separator for return thereto by gravity of heavier particles delivered therefrom, means for feeding the granular material from said container to said pipe, a source of high pressure gas having a plurality of jets distributed along the length of said pipe and directed toward the discharge end thereof, the length and diameter of pipe and the feeding means being so proportioned and arranged as to provide for packing the granular material in the pipe and to maintain the pipe packed as comminuted material passes therefrom into the separator.

6. An attrition mill comprising a supply container for granular material, a separator thereabove, an attrition pipe connected at its lower end to the bottom of said supply container and delivering into said separator at its upper end, means for supplying gas under high pressure to the lower end of said pipe and an injector in communication with the lower end of said supply container and discharging into said pipe, the inlet part of said separator communicating directly with said supply container, the outlet of said separator discharging finely pulverized material, an intermediate portion of the separator having a discharge spout associated therewith for delivering an intermediate grade of pulverized material.
